CLAIM

The ornamental design for a playing piece holder, as shown and described.

DESCRIPTION

FIG. 1 is a top view of a playing piece holder, showing the claimed design;

FIG. 2 is a bottom view of the playing piece holder shown in FIG. 1;

FIG. 3 is a side view of playing piece holder shown in FIG. 1, each side view being identical;

FIG. 4 is a top perspective view of the playing piece holder shown in FIG. 1;

FIG. 5 is a top view of the playing piece holder in a state with its moving parts in various positions;

FIG. 6 is a bottom view of the playing piece holder shown in FIG. 5;

FIG. 7 is a top perspective view of the playing piece holder shown in FIG. 5;

FIG. 8 is a top view of the playing piece holder with its lid in place;

FIG. 9 is a bottom view of the playing piece holder shown in FIG. 8;

FIG. 10 is a first side view of the playing piece holder shown in FIG. 8, the opposite side view being identical;

FIG. 11 is a second side view of the playing piece holder shown in FIG. 8, the opposite side view being identical; and,

FIG. 12 is a top perspective view of the playing piece holder shown in FIG. 8.

The broken line showing is for illustrative purposes only, and forms no part of the claimed design.
